UNITED STATES PATENT OFFICE.

JAMES McCOBB SELDEN, OF PITTSBURGH, PENNSYLVANIA, ASSIGNOR TO THE SELDEN COMPANY, OF PITTSBURGH, PENNSYLVANIA, A CORPORATION OF PENNSYLVANIA.

VAPORIZER.

1,357,525.

Specification of Letters Patent.

Patented Nov. 2, 1920.

Application filed March 15, 1918. Serial No. 222,736.

To all whom it may concern:

Be it known that I, JAMES McCOBB SELDEN, a citizen of the United States, residing at Pittsburgh, in the county of Allegheny and State of Pennsylvania, have invented 5 certain new and useful Improvements in Vaporizers, of which the following is a specification.

The present invention relates to vaporizing apparatus, particularly useful in connection with certain chemical processes, such as the saturation of an oxygen-containing, or other gas with the vapors of substances, as naphthalene, anthracene, phenanthrene, 15 toluene and the like. It may also be utilized for the purposes of separation by other methods, as in the production at different periods of substances that are respectively volatilized under different conditions.

20 In the accompanying drawings,

Figure 1 is a longitudinal sectional view through one embodiment of the invention.

Fig. 2 is a horizontal sectional view on the line 2—2 of Fig. 1.

25 Fig. 3 is a plan view of the casing structure, with the cover removed,

Fig. 4 is a cross sectional view,

Fig. 5 is a detail view on an enlarged scale, showing the joint between the cover 30 and casing.

Similar reference numerals designate corresponding parts in all the figures of the drawings.

In the embodiment disclosed, a container 35 is employed including a body casing, preferably of sheet metal, and having a bottom 6 with side walls 7 and end walls 8. A baffle plate or partition 9 extends across the casing, being suitably secured to the side 40 walls 7, said baffle terminating short of the bottom. The walls 7 and 8 and the baffle 9 are provided on their inner ends and at their upper margins with flanged strips 10 forming a groove 11, in which is placed a suitable packing 12.

A cover 13 for the casing is employed, and is provided at its edges with angle irons 14, forming depending flanges 15 that engage in the grooves and rest upon the packing, thus forming the joints. The cover 13 is relatively heavy and may be provided at its ends or at any suitable points with rings 16, or other devices, to which may be fastened elevating cables 17 that can be at-

tached to a crane or other mechanism for 55 lifting the cover.

The gas, which constitutes a vehicle for the vapors, is introduced into the casing through a conduit 18 passing through one of the end walls 8, and having a downwardly 60 extending portion 19 connected to a loop 20 located on the bottom 6 of the casing, and disposed contiguous to the side walls, as will be clear by reference to Figs. 2 and 3. The delivery end of this conduit is upturned, 65 as shown at 21, being preferably located in one corner of the casing contiguous to the end wall through which the conduit enters said casing. It is thus between said end wall and the baffle 9. The outlet for the 70 vapors or vapor-laden gases is shown at 22, and is in the end wall 8 opposite to that through which the supply conduit 18 passes.

Suitable means for determining the amount of material admitted to the casing 75 is preferably employed, said means being shown in the form of a float 23 carrying a stem 24 slidably mounted in the cover, as shown at 25. One or more wells 26 for receiving thermometers may also be provided. 80 In addition means are employed for circulating the material while being vaporized. To this end a horizontal conduit 27 is provided normally disposed in the lower portion of the casing, and having an open inlet 85 end 28 and an upturned end 29 slotted, as shown at 30, and also open. This conduit is suspended from the cover 13 by suitable straps 31, or other devices. A propeller 32 is located in the upturned end 29 of the conduit, and is carried by a shaft 33 journaled as illustrated at 34 in the cover, and having a pulley 35 on its exposed end. This pulley, as will be readily understood, is arranged to receive a driving belt operated by any 90 suitable mechanism. A feeding funnel 36 is also preferably employed, said funnel being supported by the cover projecting through the same into the lower portion of the casing.

100 With this structure, it will be evident that the gas constituting the vehicle for the vapors, as well as the vaporizing medium, will be introduced through the pipe 18, and said gas passing beneath the surface of the material will be delivered into the casing behind the baffle 9. It will traverse the casing, and finally escape through the outlet 22. By 105

reason of the coil or loop 20, the gas and material will be caused to have substantially the same temperature, and the vaporizing action can be secured by heat; either the 5 gas being preheated or the container can be heated, as desired. It will be noted that the agitator and all the instruments are supported by the cover, so that when said cover is elevated, the entire interior of the casing 10 is exposed and unobstructed. This apparatus may be employed in other ways. For example, the material to be acted upon may be placed in the container and heated to a 15 temperature between the melting and boiling points, depending upon the nature of the material. The current of gas is led over the molten material in the container, and thereby becomes saturated with the vapor from the material. The gas stream is then 20 conveyed from the container into a suitable condensing chamber.

From the foregoing, it is thought that the construction, operation and many advantages of the herein described invention will 25 be apparent to those skilled in the art, without further description, and it will be understood that various changes in the size, shape, proportion and minor details of construction, may be resorted to without departing 30 from the spirit or sacrificing any of the advantages of the invention.

Having thus fully described my invention, what I claim as new, and desire to secure 35 by Letters Patent, is:—

1. In apparatus of the character set forth, the combination with a casing, of means connected to the casing for passing a vaporizing gas through the same, a removable cover for the casing, a conduit in the 40 casing having open ends at different elevations within said casing and adapted to enter the material placed in the casing, means suspending the conduit from the cover to permit the removal of both together, and a propeller supported on the cover and operating in the conduit and driving means for propeller projecting from the cover, said propeller and driving means being removable with the cover.

2. In apparatus of the character set forth, the combination with a container for the

material to be vaporized, comprising a body and a cover removably mounted thereon, of means for removing the cover from the body, means connected to the body for supplying a gaseous vehicle thereto, means connected to the body for carrying off the vapor laden gaseous vehicle, a conduit in the body having angularly disposed portions, one of which is upstanding, hangers that suspend 55 the conduit from the cover and cause its removal therewith, a propeller located in the upstanding portion of the conduit, and a driving shaft for the propeller journaled in the cover and having its upper end disposed 60 above the same.

3. In apparatus of the character set forth, the combination with a casing body having an open top, of a removable cover for the open top, means connected to the body for introducing a gaseous vehicle thereto and for carrying off the vapor-laden gases, baffle means fixed in the body, and agitating means supported by and removable with the cover, said agitating means extending below and 70 being located at one side of the baffle means when the cover is in place and being removable with said cover without interference 75 with the baffle means.

4. In apparatus of the character set forth, the combination with a casing body having an open top, of a baffle plate extending across the body, means for introducing a gaseous vehicle into the casing body on one side of the baffle plate, means for carrying 85 off the vapor-laden gases from the body on the opposite side of the plate, a cover removably mounted on the body, means providing a gas-seal between the cover and body and between the cover and baffle plate, and agitating means suspended from and removable with the cover, said agitating means being located on one side of the baffle plate and including an operating device projecting 90 above the cover.

In testimony whereof I affix my signature in the presence of two witnesses.

JAMES McCOBB SELDEN.
